UNITED STATES PATENT OFFICE.

AUSTIN K. HOYT, OF SYRACUSE, NEW YORK.

DESIGN FOR A BRACE FOR FOLDING CHAIRS.

SPECIFICATION forming part of Design No. 26,991, dated April 27, 1897.

Application filed March 22, 1897. Serial No. 628,782. Term of patent 7 years.

To all whom it may concern:

Be it known that I, AUSTIN K. HOYT, a citizen of the United States, residing in the city of Syracuse, county of Onondaga, and State of New York, have invented and produced a new and original Design in Straps or Braces for Folding Chairs, of which the following is a specification, reference being had to the accompanying drawings, in which—

10 Figure 1 shows a side view thereof. Fig. 2 shows an edge view thereof, these two views being deemed sufficient to fully illustrate my design.

15 The leading feature of my design consists in a strap enlarged at one end, forming a unitary article.

a is the body of the strap, preferably of uniform size throughout its entire length and

having one end rounded, as shown at *a'*, and provided with an opening *b*. The opposite 20 end is enlarged at right angles, as shown at *c*, and provided with an opening *d*, rectangular outlines of the whole producing a pleasing effect to the eye.

Having described my invention, what I 25 claim, and desire to secure by Design Letters Patent, is—

A design for a strap or brace for a folding chair, substantially as herein described and shown.

In witness whereof I have hereunto set my hand this 19th day of March, 1897.

AUSTIN K. HOYT.

In presence of—

MARY A. FRANKLIN,
HOWARD P. DENISON.
